UNITED STATES PATENT OFFICE.

PIETER DANIEL VAN ESSEN, OF HAAG, NETHERLANDS, AND CLARENCE HERVY FROELICH, OF BETHLEHEM, PENNSYLVANIA.

BREECH MECHANISM.

Application filed July 18, 1924. Serial No. 726,659.

Our invention relates to the construction of a breech mechanism for a gun, and is more particularly intended for use in smooth bore guns and trench mortars adapted to fire 5 projectiles of rearwardly tapering or of stream line form that leave a substantial amount of free space between their walls and the bore of the gun, as for example, projectiles of the type mentioned in a co-pending application for a patent by Pieter Daniel Van Essen, Serial No. 713,513, filed 10 May 15, 1924.

Smooth bore guns, such as trench mortars or infantry howitzers, are intended to fire a 15 comparatively heavy projectile at low muzzle velocities, conditions in which it is difficult to obtain constant ballistics. For this reason, quick burning powders are preferred, but their use has hitherto necessitated the reinforcement of the gun almost 20 to its muzzle in order to withstand the high pressures generated therein. This results in an appreciable increase in the weight of the gun and impairs its mobility.

25 The use of trench mortars by infantry from a covered position requires that their position shall not be disclosed to the enemy. The muzzle flame or flash at the discharge 30 of the projectile from a gun enables the enemy to locate its position, and this is more especially so during a night attack. This flash is caused by the self ignition of combustible but unconsumed gases when they 35 come into contact with the air, which supplies the oxygen for combustion in which the said gases are deficient. These gases leave the muzzle of the gun at high temperature and pressure, and at a short distance away from the gun they become sufficiently 40 mixed with the surrounding atmosphere to become ignited and produce a luminous flame of spherical shape which immediately discloses the position of the gun. This phenomenon is the more pronounced in the case 45 of quick burning powders. It has been attempted to overcome this in certain cases by

the addition of small quantities of oxygen carrying material to the composition of the propellant powder, with the object of effecting 50 a more complete combustion within the bore of the gun and also obtaining a more regular burning of the powder. While such additions do reduce the muzzle flame, they

nevertheless act as smoke producers, so that when fired in daylight they still disclose 55 the position of the gun. It is, therefore, highly desirable to obviate the muzzle flame by some other means than those referred to.

An object of our invention is to provide 60 a propellant charge chamber for a gun having restricted communication with the latter, whereby pressures will be better distributed throughout the passage of the projectile through the bore of the gun, thereby making it possible to use a lighter tube construction, 65 and whereby combustible material and gases are more completely consumed thereby avoiding muzzle flame or an undue amount of smoke when firing.

A further object of our invention is to 70 provide an improved type of breech block mechanism incorporating a propellant charge chamber having restricted communication with the interior of a gun tube.

A further object of our invention is to 75 provide a breech block incorporating a powder chamber open at its rear end and having restricted communication with the bore of a gun, together with a transversely movable closure member for the open end of the 80 chamber and carrying a firing device, the closure member in one position exposing the open end of the powder chamber and in its other position having the firing device over the said chamber.

85 A further object of our invention is to provide breech mechanism incorporating a block having a bore and an interrupted thread connection with respect to a gun and carried by a carrier ring, which is pivotally mounted with respect to the gun tube, together with a closure member transversely movable with respect to the block and carrying a firing device, the transversely movable member in one position exposing the 90 bore of the block and in its other position having the firing device arranged over the bore.

95 A further object of our invention is to provide breech mechanism for a gun including 100 a block having an interrupted thread connection with respect to the bore of the gun and being rotatably carried by a carrier ring hinged at one side of the gun together with means for rotating the block to release 105 the interrupted thread connection and latch

mechanism for holding the block in fixed position with respect to the ring after the block has been moved a sufficient angular distance to release the interrupted thread connection.

A further object of our invention is to provide breech mechanism for a gun incorporating a block having an interrupted thread connection with respect to the bore 10 of the gun and including an axially arranged propellant charge chamber open at its rear end, a carrier ring rotatably supporting the block and hinged laterally with respect to the gun, a closure member transversely 15 slidable with respect to the block and in one position exposing the open end of the propellant charge chamber and in its other position closing such chamber, together with mechanism for turning the block and moving the closure member transversely.

A further object of our invention is to provide a gun incorporating a breech block which includes a propellant charge chamber which has ports for affording communication 25 between the propellant charge chamber and the gun tube together with a non-erodible lining which surrounds and is spaced from the outer ends of the ports.

In the drawings accompanying this specification, we show:

In Fig. 1, a rear end elevation of the breech mechanism;

In Fig. 2, a longitudinal section through the breech end of the gun with the swinging breech block in elevation and the sliding block in section;

In Fig. 3 a longitudinal section of the swinging breech block in its closed position in the gun;

40 In Fig. 4 a cross sectional view on line IV—IV of Fig. 2 with the sliding block in section and the rear end of the swinging breech block and the extractor exposed to view;

45 In Fig. 5 a detailed view in longitudinal section of the extractor mechanism, indicated in Fig. 2 by dotted lines;

In Fig. 6 a cross sectional view on line VI—VI of Fig. 1; and,

50 In Fig. 7 a detail section VII—VII of Fig. 4, showing one of the inclined guides of the rectangular portion of the breech block and its relation to the sliding block.

Referring now to the drawings for a better understanding of our invention, in 55 Figs. 2 and 3, we show a gun tube 10, a breech ring 11 rigidly secured to the gun tube and having internal screw threads in the usual manner, also having the trunnion bracket 17 and the trunnion pin 13. The carrier ring 14 supports the swinging screwed breech block 15 by the rearward prolongation of the breech screw thread 16 and is adapted to swing about the trunnion 60 pin 13 by means of the brackets 12. We also

show a locking bolt of the conventional type for locking the carrier ring and the breech block, said locking bolt consisting of the bolt 20 adapted to engage with a notch 19 in the breech screw and having at its outward end a portion 21 engaging one arm of a bell crank lever 22, the lever being pivoted by the pin 23 to the carrier ring 14 and having its other arm engaged by a spring 24. From this, it will be apparent that the spring 24 tends to tilt the bell crank lever 22 to urge the bolt 20 inwardly so that it may enter the notch 19 when it comes opposite to the latter.

The contour of the swinging breech block may be such as to conform to any type of breech seating in general use, that is to say, it may be cylindrical or ogival. The breech threads may likewise be designed in any suitable manner. In the drawings, we show 80 a swinging screwed block of the conventional cylindrical type with interrupted threads, but having certain important and novel modifications thereto, which render it particularly adapted to guns, wherein an even and regular muzzle velocity is difficult of attainment.

The main body of the breech block 15 (Fig. 3) is bored out to receive a combustion chamber 30, secured to it by the threaded portion 31 and centrally disposed in the said bore. The liner 32 of non-erodible material fits closely the bore of the breech block and is held in position by screw threads 33, so as to be easily replaceable. The thickness of this liner is such as to leave an annular clearance 34 between the combustion chamber 30 and the inner wall of the liner 32. The body of the breech block projects rearwardly of the carrier ring 14, said projecting portion being of rectangular section. The breech block is also bored out from this rearward projecting end to form a propellant charge or cartridge case chamber 18. An obturator 60 of the Broadwell ring type is 100 shown forwardly of the breech block 15.

In Figs. 2 and 3, we show two external guide slots 25 parallel to each other and cut in the rectangular portion of the breech block in a direction transverse to the gun axis. The rearward faces 26 of these slots are, however, inclined transversely of the axis of the gun, as clearly shown in Figs. 2 and 7. The rear face 27 of the breech block is likewise faced off at the same angle of inclination, but a seat 28 whose plane is normal to the gun axis is provided for the head of a cartridge case so as to hold same centrally along the axis of the gun. The recess 29 in the seat 28 is adapted to contain the forked end of an extractor 50 and the breech block is also suitably recessed for the swinging of the extractor pivot in a recess 53.

The combustion chamber 30 is of hollow 130

construction but closed forwardly. The chamber walls are designed to safely withstand the maximum pressures developed by the combustion of the propellant powder in the powder chamber 18. A number of radial channels or vents 35, preferably four in number, angularly equidistant from each other, are provided in the walls of the combustion chamber 30 to communicate the propellant gases from said chamber to the annular clearance 34, which is in open communication with the gun. The open end 36 of the combustion chamber is slightly enlarged so as to correspond with the propellant charge chamber 18 and be adaptable to the mouth of a cartridge case when such is used. In Figs. 3 and 5, we show a cartridge case 37 in the firing position.

The sliding block 40 occupies a position rearwardly of the swinging block 15 and is intended to securely close the propellant charge chamber 18, when the block is centrally disposed in relation to the swinging block 15. This sliding block is of substantially rectangular shape with its upper and lower edges slightly arched and has a portion 41 cut away to a radius corresponding with the bore of the powder chamber 18, as shown in Fig. 1. At the lower corner of the sliding block, on the side opposite to the trunnion brackets, a depending lug 42 is provided having a groove or slot 43 adapted to engage with a pin 44 which is fixed to the carrier ring 14 (see Fig. 6).

The sliding block 40 is attached to the breech block 15 by means of ribs 45 which engage in the guide slots 25 (Figs. 2, 3, 5 and 7), the rearward faces 46 of said ribs being inclined at an angle to correspond with and be in contact with the inclined faces 26 of the guide slots. This permits of the movement of the sliding block transversely to the gun axis, while also providing a slight rearward withdrawal of the sliding block from the face of the swinging breech block, the inclined contacting surfaces of the guide slots and the ribs providing a wedge action. The sliding block also carries rearwardly a firing mechanism 47 of the usual type, such for example, as the Tasker firing mechanism, having a firing lever 48, a suitable aperture 49 being provided in the sliding block face for the protrusion of the firing pin when it is desired to fire the gun.

The propelling charge can be inserted in bags or in cartridge cases. In the latter case it is necessary to provide a means for extracting the cartridge case from its seating, after same has been fired. We, therefore, show in Figs. 2, 3, 4 and 5, a suitable method of achieving this object. The extractor 50 consists of a semi-circular forked portion 51 adapted to closely fit under and around the head of the cartridge case, a pivoting portion 52 suitably supported in the recess 53 of the breech block and a finger portion 54, adapted to engage in the guide slot 55 of the sliding block. This guide slot 55 is positioned to one side of the vertical axis of the gun and is disposed transversely of the gun and parallel to the guide slots 25. It extends from a point near the outer edge of the sliding block to a point substantially in line with the cartridge case seating 28 where it terminates in a radial slope 56. The spring plunger 57 is disposed angularly to the said slot and is adapted to cause the finger portion 54 of the extractor to over-ride it during the outward and transverse motions of the sliding block and the guide slot 55. The over-riding of the finger 54 by the spring plunger 57 effects the displacement of the former about the pivot 52 and results in the rearward displacement of the forked portion 51 away from the recess 29 in the swinging breech block. During the movement of the sliding block in the reverse direction, that is, towards the axis of the gun, the face of the finger 54 contacts with the plunger 57 and forces it out of its protruding position in the slot 55, thereby permitting said finger to retain its contact in the slot throughout the travel of the latter.

To facilitate rotation of the swinging breech block a hand lever 58 is provided, said hand lever being suitably attached to the rectangular portion of the breech block. The operation of our breech mechanism is as follows: In order to effect the disengagement of the interrupted threads of the swinging breech block 15 from the corresponding threads in the breech ring 11, the swinging block is rotated through an angle of 90° by means of the lever 58. The sliding block 40, being attached to the swinging block 15 by the ribs 45 engaged in the guides 25, is capable of transverse movement relatively to the swinging breech block while also rotating with it. Its free rotation while occupying a constant relative position to the breech block is, however, limited by the confines of the tangential guide slot 43 which engages with the fixed pin 44 of the carrier ring 14. This results in a combined angular and transverse displacement of the sliding block 40 in respect to the gun, until the breech block 15 having been rotated through 90 degrees, the sliding block 40 occupies a position such as is indicated in the dotted lines of Fig. 1. In this position the powder chamber 18 is exposed. The movement of the sliding block to this outwardly projecting position also effects the rearward movement of the forked portion 51 of the extractor 50 due to displacement of the finger 54 by contact with the plunger 57 and facilitates extraction of the cartridge case after firing.

The powder chamber being thus exposed,

130

the opening of the breech of the gun is effected by swinging the complete mechanism, viz, the carrier ring 14, the swinging breech block 15, the expansion chamber 30, 5 the sliding block 40 and the firing gear 47, away from the confines of the breech ring 11, by means of the carrier ring brackets 12 which pivot about the trunnion pin 13. The breech block 15 is free to rotate in the carrier ring 14 from the "engaged" to the "disengaged" positions of its interrupted threads, owing to the small notch 19 in the breech block which during rotation to the disengaged position is moved into alignment 10 with the locking bolt 20, so that said locking bolt being actuated by the cam lever 22 and the compression spring 24 engages with this notch as soon as the breech threads are fully disengaged, and in this manner 15 locks the breech block to the carrier ring and permits the block to be swung out or swung back to its seating by the lever 58 without loss of its proper position in respect of its interrupted threads.

20 25 After the cartridge case is inserted in the powder chamber 18, the breech block 15 is caused to reengage with the breech ring threads by the reversed rotation of the breech block and the lever 58. During this 20 rotation, a transverse movement of the sliding block 40 is again effected, by the engagement of the slot 43 with the fixed pin 44, said movement being, however, in a direction opposite to that already described, in other words, the powder chamber 18 is 25 gradually closed by the interception of the sliding block 40 and the firing pin of the firing gear 47 is brought to a position coincident with the axis of the gun and the center of the cartridge case in the powder chamber 18, and ready to impact with the firing cap of the cartridge primer upon release of the firing lever 48.

30 35 Owing to the use of a substantially closed combustion chamber, the gas pressure developed by the firing of the powder in the cartridge case is restrained from immediate expansion into the free space in the gun, and an average pressure can be maintained 30 in the gun by means of the distributing channels 35 and the annular clearance 36. This restraint produces a building up of pressure in the combustion chamber over and above the pressures developed by the normal burning of the propellant powder. The building up of this pressure also increases the rate of burning of the powder with the result that a high local pressure is rapidly 35 accumulated in the explosion chamber, which is designed so as to be fully capable of withstanding this high pressure. The restricted outlets 35 serve to distribute this pressure evenly to the bore of the gun during the whole of the travel of the projectile along the bore, with the result that

a moderate average pressure is maintained in the gun until the projectile has been discharged.

Furthermore, the use of a special combustion chamber permits of a substantially 70 complete combustion of the propellant powder in the chamber itself so that only non-combustible and permanent gases are passed to the bore of the gun. Even if some small 75 amount of combustible gas does pass to the gun, the loss of temperature due to its expansion results in the cooling of said gases below their incandescent state. Hence no 80 muzzle flame will be produced. The gases enter the bore of the gun at high temperature and high velocity and for this reason, we provide the liner 32 of erosion resisting 85 steel, where erosion is likely to take place.

We do not limit our invention to the particular design and the method of construction we have here described, as it is evidently susceptible of various modifications, apparent to anyone skilled in the art, without departing from the spirit of our invention. We intend that only such limitations 90 shall be placed thereupon as are imposed by the prior art or as are specifically set forth in the appended claims.

Having thus described our invention what we claim as new and desire to secure by Letters Patent is:

1. In a gun, the combination of a member having a propellant powder chamber therein, said chamber being of substantially smaller diameter than the bore of the gun, whereby an annular clearance may be provided between the chamber and the gun when the former is within the confines of the latter, and a pivotal connection between the tube and the member.

2. In a gun, the combination of a member having a propellant powder chamber therein, means for pivotally connecting the member and the gun, and pressure distributing means for applying a substantially constant average pressure to the bore of the gun during the combustion of the propellant charge and until the projectile has been discharged from the gun.

3. In a gun, the combination of a member having a substantially closed powder chamber therein, means for pivotally connecting the member and the gun, and a pressure throttling means in the powder chamber directly communicating with the bore of the gun for regulating the admission of the powder pressure thereto on the firing of the propellant charge.

4. In a gun, the combination of a member having a substantially closed powder chamber therein, restricted outlets in the powder chamber directly communicating with the bore of the gun to delay the expansion of the combustion gases due to the ignition of a propellant powder disposed

within the chamber, and means for pivotally connecting the member to the gun so as to intercept the bore of the gun in one position of said member, while permitting 5 the insertion of a projectile in the gun bore, in the other position of the member.

5. The combination, with a gun, of a pressure accumulator adapted to communicate with the bore, means for pivotally connecting the accumulator to the gun, said accumulator adapted to store permanent gases at high temperatures and high pressures resulting from the combustion of a propellant powder charge, and means to apply said 10 gases to the gun at substantially reduced temperatures and pressures.

6. The combination, with a gun having a breech block receiving portion axially aligned therewith, of a breech block for said 20 portion having a propellant charge chamber closed at its forward end and open at its rearward end, said block having means for affording restricted lateral communication between the chamber and the interior 25 of the gun.

7. In a gun, the combination of a gun tube, a member adapted to fit in the breech end of the tube and having a powder chamber adapted to contain a charge of propellant powder, the bore of the tube being adapted to contain a projectile forwardly of the member, and the member having an intercepting wall between said powder chamber and the tube and said wall being 35 provided with small perforations to oppose entry into the bore of unconsumed combustible gases capable of causing muzzle flame.

8. In a gun, the combination of a tube having an axial bore for a projectile, a breech mechanism for the tube, said mechanism including a powder-chamber-defining 40 member adapted to project within the bore of the gun when the breech is closed and being of smaller diameter than the bore of the tube so as to provide an annular clearance for the passage of gun gases about the periphery of the member, the member being 45 adapted to be withdrawn from the confines of the tube, and means to effect seating and 50 withdrawal of said member.

9. In a gun, the combination of a gun tube, a breech block for the gun tube and provided with a rearwardly-open powder chamber, a member for opening and closing 55 the powder chamber, and a firing device carried by the member, said block having restricted passages to afford communication between the powder chamber and the bore of the tube to provide for even distribution 60 of gas pressure to the latter.

10. In a breech mechanism for a gun, the combination of a rotatable screwed closure member intercepting the bore of the gun and having a rearwardly open powder chamber, a transversely slidable closure member 65

intercepting the open end of the powder chamber, a firing device carried by the slidable closure member, said first closure member having restricted passages to afford communication between the powder chamber 70 and the bore of the gun for the even distribution of gas pressure to the latter, means to impart rotation to the screwed closure member to release the latter from the gun, means dependent upon angular movement 75 of the screwed closure member for imparting transverse movement of the second closure member, and means providing for the withdrawal of the first closure member from its intercepting position after a predetermined angular movement thereof. 80

11. In a breech mechanism for a gun, the combination of a rotatable screwed closure member adapted to intercept the bore of the gun and having a rearwardly open powder 85 chamber, a transversely slidable closure member for intercepting the open end of the powder chamber, a firing device carried by the transverse closure, said first closure having passages to afford restricted communication between the powder chamber and the bore of the gun, means to effect the withdrawal of the closure members from their respective intercepting positions, and an extractor to withdraw a cartridge case 90 from the powder chamber actuated by the slidable closure member when it moves relatively to the screwed closure member. 95

12. In a gun, the combination of a breech closure member having a powder chamber 100 provided with restricted outlet means, a closure member for the powder chamber, a firing device carried by the powder chamber closure member, and mechanism for moving both closure members to open and closed 105 positions.

13. In a gun, the combination of a breech closure member having a propellant powder chamber with restricted outlet means and adapted to receive a cartridge case containing the propellant charge, a closure member for the powder chamber, a firing device carried by the powder chamber closure member, mechanism for moving both closure members to open and closed positions, and extracting means to withdraw the cartridge case from the powder chamber, said extracting means being actuated by the movement of one closure member relatively 110 to the other closure member during a phase 115 of the opening movement of the first-named member. 120

14. The combination with a gun, of a breech block provided with a propellant charge chamber and having an interrupted 125 thread connection with respect to the gun, a carrier ring for the block, a pivotal connection between the gun and the carrier ring, a closure member movable transversely of the block and in one position exposing the pro- 130

pellent charge chamber for loading, and means dependent upon rotary movement of the block and of the member for sliding the latter transversely.

5 15. In a breech mechanism for a gun, the combination of a main rotatable portion adapted to close the breech and bored to receive a powder charge, a transversely slideable portion rearwardly attached to the 10 main rotatable portion, said slideable portion having a guide slot therein, and a fixed pin attached to the gun and adapted to engage the guide slot, whereby rotation of the main portion effects the movement of the 15 slideable portion in a relatively transverse direction.

16. In a breech mechanism for a gun, the combination of a main rotatable portion adapted to close the breech and bored to receive 20 a powder charge, a slideable portion carried by the main rotatable portion, a guide slot disposed in the slideable portion, a fixed pin attached to the gun and adapted to engage the guide slot, whereby rotation 25 of the main portion effects the movement of the slideable portion in a relatively transverse direction, a lever for effecting said rotation of the main portion, a cartridge ejector operable by the transverse movement 30 of the slideable portion, and a firing device attached to the slideable portion.

17. In a gun, the combination of a breech ring provided with threads, a swinging breech block having threads for engagement 35 with the ring threads and provided with a rearwardly opening combustion chamber for the propellant charge, means to effect the withdrawal of the screwed breech block from the confines of the breech ring, a sliding block disposed rearwardly of the breech block to close the explosion chamber, means to effect the movement of the sliding block transversely to the axis of the gun, and guide means for confining said transverse 45 movement to the closing and opening of the combustion chamber.

18. In a gun, the combination of a breech ring having interrupted internal threads, a breech block having interrupted external 50 threads for engagement and disengagement with the threads of the breech ring, a carrier for supporting the breech block, said breech block having a propellant charge chamber open at its rear end, means for effecting the 55 engagement and disengagement of the threads, means for interlocking the carrier and the breech block after such disengagement has been effected to prevent relative rotary movement therebetween, means providing for movement of the carrier to insert 60 and to remove the breech block from the confines of the gun, a sliding block closure to intercept the open end of the chamber, an interlocking guide connection between 65 the closure and the breech block and dis-

posed transversely thereof, means responsive to rotary movement of the breech block to effect transverse movement of the closure, a firing device attached to the closure, and means for throttling the passage of gases 70 from the chamber to the bore of the gun.

19. In a gun, the combination of a breech ring having interrupted internal threads, a breech block having interrupted external threads for engagement and disengagement 75 with the threads of the breech ring, a carrier for the breech block, a pivotal connection between the carrier and the gun, said breech block having a combustion and a propellant powder chamber, means for effecting the engagement and disengagement of the threads, means for interlocking the carrier and the breech block after disengagement of the threads has been effected to prevent relative 80 rotary movement between the ring and the block, a sliding block closure for the powder chamber, an interlocking guide connection between the closure and the block and disposed transversely of the latter, means responsive to rotary movement of the block 85 to impart transverse movement to the closure, a firing device attached to the sliding closure, means for throttling the passage of propellant gases from the combustion chamber to the bore of the gun, and means for 90 ejecting a cartridge case from the chamber dependent upon transverse opening movement of the closure.

20. The combination of a gun and breech mechanism, the gun being arranged to receive a projectile forwardly of the breech mechanism and the breech mechanism being adapted to receive a cartridge case containing propellant powder, the breech mechanism including a major breech closure member having a chamber for a cartridge case and a septum wall for separating the chamber from the projectile, a minor breech closure for opening and closing the cartridge case chamber, said minor closure having a 100 guide slot, a fixed extracting lever pivotally attached to the major closure, the lever having a forked member to engage a cartridge case and a finger member to engage the 105 guide slot in the minor closure, and a spring plunger radially inclined to the axis of the gun and disposed in the minor closure so as to intercept the guide slot, whereby the outward transverse movement of the minor closure relatively to the major closure causes the finger member of the extractor to override the spring plunger and effect the rearward displacement of the forked member, whereas the inward transverse movement of the minor breech closure causes the finger member to compress the spring plunger from its intercepting position, without 110 effecting the displacement of the forked member.

21. In a breech loading gun having a 130

- propellant powder chamber member independent of the gun tube, the combination of a forward breech closure, a rearward breech closure, means to move the latter to open and to close said powder chamber, and means to move the former to open and to close the gun bore.
22. In a breech loading gun having a propellant powder chamber member independent of the gun tube, the combination of a main breech closure rearwardly closing the bore of the gun, a closure rearwardly closing the powder chamber, and mechanism for opening and closing both closures.
23. In a breech loading gun having a propellant powder chamber member independent of the gun tube, the combination of a main breech closure rearwardly closing the bore of the gun, a closure rearwardly closing said powder chamber, means for moving the main breech closure, and means dependent upon movement of the main breech closure for moving the powder chamber closure.
24. In a breech block for a gun, the combination of an outer member having a passage extending therethrough, said passage having portions of small and large diameter and a portion of small diameter being adapted to receive a cartridge case, an inner shell member having a chamber open at one end and having its open end secured to the outer member with the chamber thereof aligned with the cartridge case portion of the passage of the outer member, the inner member being smaller than the portion of the passage of the outer member of larger diameter, whereby a space is provided between the inner and the outer members, and the inner member being provided with ports extending through the wall thereof for affording communication between its chamber and the space between the inner and the outer members.
25. In a breech block mechanism, the combination of a member having an axial passage consisting of three portions of successively larger diameters, the first portion being adapted to receive a cartridge case, a hollow member open at one end and arranged within the portions of the first member of intermediate and largest diameters and having its open end secured in the passage of the first member of intermediate diameter, said second member having radial ports for affording communication between the chamber thereof and the space between the first member and the hollow member.
26. In a breech block mechanism for a gun, the combination of a first block member having an axial passage consisting of three portions of successively larger diameters and the first portion being adapted to receive a cartridge case, a second member having a chamber and open at one end, the open end being connected to the portion of the passage of the first member of intermediate diameter, the second member being provided with ports for affording communication between the chamber thereof and the space between the first and the second members, and a protective lining for the portion of the passageway of the first member of largest diameter.
27. In a breech block mechanism for a gun, the combination of inner and outer block members which together define a propellant charge chamber closed at its forward end, the inner and the outer members being spaced apart from the forward ends thereof rearwardly and the inner member being provided with lateral ports to afford restricted communication between the propellant charge chamber and the space between the members, and a substantially non-erodible lining for the outer member in the space between the inner and the outer members.
28. The combination with a gun having a breech block receiving chamber provided with interrupted threads, a breech block having interrupted threads to be engaged and disengaged with respect to the threads of said chamber, a carrier ring for the breech block, a pivotal connection between the carrier ring and the gun, means for turning the block to engage and disengage the interrupted threads, said block having a rearwardly opening propellant charge chamber, a member carried by and movable transversely of the block to cover and uncover the chamber, and mechanism arranged between the carrier ring and the transversely movable member for imparting transverse movement to the latter member when the block is turned.
29. The combination with a gun having a breech block receiving chamber provided with interior interrupted threads, of a block having interrupted threads to fit the interrupted threads of said chamber, a carrier ring having threads to fit threads on the block, a pivotal connection between the carrier ring and the gun, means for turning the block with respect to the carrier ring to engage and disengage the interrupted threads, said block being provided with a propellant charge chamber opening rearwardly, a member carried by and movable transversely with respect to the block for covering and uncovering said chamber, firing mechanism carried by said member and arranged to be over the chamber when the member covers the latter, and a cam connection between said member and the carrier ring whereby upon turning of the block and of said member the latter is caused to move transversely to cover or uncover the propellant charge chamber.
30. The combination with a gun having a breech block receiving chamber provided with interior interrupted threads, a breech block having external threads with the for-

ward portions thereof interrupted to fit the interrupted threads of the chamber, a carrier ring having threads to fit the rearward threads of the block, a pivotal connection between the carrier ring and the gun, means for turning the block with respect to the carrier ring to engage and disengage the interrupted threads, said block having a propellant charge chamber opening rearwardly, a transversely movable member having a guide connection with respect to the block for covering and uncovering the propellant charge chamber, mechanism arranged between the carrier ring and said member, whereby upon turning of the block and of said member, the latter is caused to move transversely to cover and uncover the propellant charge chamber, an ejector carried by the block and having a portion to eject a cartridge case from the chamber, and means carried by the transversely movable member for operating the ejector upon movement of the transversely movable member in a direction to expose the propellant charge chamber.

31. The combination with a gun having a breech block receiving chamber provided with interior interrupted threads, a breech block having forward interrupted threads to fit the interrupted threads of the chamber and rearward threads, a carrier ring having interior threads fitting the rearward threads, a pivotal connection between the carrier ring and the gun, means for turning the block with respect to the ring to engage or disengage the interrupted threads, latch mechanism carried by the ring for holding the block in a fixed position with respect to the ring when the interrupted threads are disengaged, said block having a rearwardly open propellant charge chamber, a member carried by and movable transversely with respect to the block to cover and uncover the chamber, firing mechanism carried by said member and arranged to be over the chamber when the member covers the latter, cam mechanism arranged between the transversely movable member and the ring for imparting transverse movement to said member upon rotary movement of the block and of said member, an ejector carried by the block and having a portion to engage a cartridge case inserted in the chamber, and means carried by the transversely movable member for actuating the ejector when said

member is moved in a direction to uncover the propellant charge chamber.

32. The combination with a gun having a breech block receiving portion, of a breech block for said portion having a propellant charge chamber closed at its forward end and open at its rearward end, said block having means for affording restricted lateral communication between the chamber and the interior of the gun. 60 65

33. The combination with a gun, of a breech block adapted to fit within the breech end of the gun and having an explosion chamber, means for inserting and withdrawing the breech block, and means for affording restricted communication between said chamber and the bore of the gun. 70

34. In a gun, the combination of a gun tube, a member having an expansion chamber therein, said member being rearwardly disposed in the gun, a block member insertable and removable with respect to the tube and defining a powder chamber, means to fire the powder in the powder chamber, means to connect the block to the expansion 80 85 chamber member so as to communicate the gases of combustion to the latter, and means for conducting the expanded gases to the gun tube at an average pressure during the combustion of the powder. 85

35. In a gun, the combination of a gun tube, a member having an expansion chamber therein, said member being rearwardly disposed in the gun, a gas generator member for propellant gases in direct communication with the expansion chamber and pivotally connected to the gun, means to effect said communication, and means for conducting the expanded gases to the gun tube at an average pressure until the discharge of a projectile from the gun tube. 90 95

36. In a gun, the combination with a gun tube, of a breech block for the tube, said block having an expansion chamber for gases resulting from the combustion of a propellant charge, and means affording restricted communication between the chamber and the tube. 100 105

In testimony whereof I hereunto affix my signature this 7th day of July, 1924.

PIETER DANIEL VAN ESSEN.

In testimony whereof I hereunto affix my signature this 16th day of July, 1924.

CLARENCE HERVY FROELICH.
